(57) **CLAIM**

The ornamental design for a reusable adhesive strip, as shown and described.

DESCRIPTION

FIG. 1 shows a perspective view of a reusable adhesive strip; FIG. 2 shows a front view of the reusable adhesive strip; FIG. 3 shows a rear view of the reusable adhesive strip; FIG. 4 shows a top plan view of the reusable adhesive strip; FIG. 5 shows a bottom plan view of the reusable adhesive strip; FIG. 6 shows a right side view of the reusable adhesive strip; and, FIG. 7 shows a left side view of the reusable adhesive strip. The shade lines in the Figures show contour and not surface ornamentation.

1 Claim, 4 Drawing Sheets
